UNITED STATES PATENT OFFICE.

LEWIS BERGAN, OF DUNN CENTER, NORTH DAKOTA.

CIGAR HOLDER.

Application filed March 14, 1923. Serial No. 625,143.

To all whom it may concern:

Be it known that I, LEWIS BERGAN, a citizen of the United States, residing at Dunn Center, in the county of Dunn and State of North Dakota, have invented certain new and useful Improvements in a Cigar Holder, of which the following is a specification.

This invention relates to improvements 10 in cigar holders and has for its prime object to provide a device of this character with means positioned within the holder by which a cigar may be firmly engaged and adapted to hold said cigar until same has 15 been consumed to a point where the fire of the cigar reaches the holder.

A further object of the invention is to provide a cigar holder having a pair of spring clamping members secured within 20 the holder, so that the same will automatically engage and hold a cigar of any size.

A still further object of my invention is to provide a cigar holder of the above indicated character, which is simple in construction, durable, efficient for the purpose intended, and one that can be manufactured and placed on the market for sale at a relatively low cost.

These and like objects of the invention 30 will be better understood as the description follows and as is specifically pointed out in the appended claims.

Referring to the accompanying drawing which forms a part of this specification and 35 which clearly illustrates the construction and operation of my cigar holder.

Figure 1 is a longitudinal section through 40 a cigar holder constructed in accordance with my invention, showing a cigar mounted within the holder.

Figure 2 is a section taken on line 2—2 of Figure 1.

Figure 3 is a view looking at the open or bowl end of the holder, and

Figure 4 is a perspective view of one of the clamping members.

Referring to the accompanying drawing in detail, like characters will be used to designate like parts in the different views.

In the drawing, the cigar is indicated by the numeral 1, the holder as 2 having a central draft passage 3 in the stem 4 and a bowl 5 formed in one end of the holder 2, all of which is of the usual construction.

In order to retain a cigar of any diameter, wherein the end of the cigar does not ex-

ceed the diameter of the bowl 5, a pair of spring clamping members 6 are provided, which are formed with a tongue 7 at right angles to the clamping members 6, so that the tongues 7 are embedded in the edge of the holder surrounding the bowl 5, as indicated by the numeral 8. The spring clamping members 6 are semi-circular in formation, so that when same are placed within the bowl of the holder, the two members cooperate to form a clamping band. The semi-circular formation of the clamping members 6 has a tendency to force the said clamping members towards the center of the bowl, thus enabling same to firmly grip and hold a cigar, as is indicated in Figure 1.

In view of the foregoing description of my invention, taken in connection with the accompanying drawing, it is thought that any further explanation as to the construction, operation, and objects of my improved cigar holder is unnecessary.

While I have shown and described the preferred form of my invention, I realize that various minor changes may be resorted to, without departing from the spirit and scope of the invention as claimed, and therefore, I do not wish to limit myself to the exact details of construction shown, nor to the combination and arrangement of parts.

What I claim as new and desire to secure by Letters Patent is:

1. A cigar holder comprising a cigar receiving bowl formed in one end thereof, a central draft passage in the opposite end and communicating with said bowl, a pair of semi-circular spring clamping members each having one end thereof secured in the open end of said bowl, said clamping members having their opposite ends extending past the secured end of each other to form a clamping band.

2. A cigar holder of the class described comprising a cigar receiving bowl formed in one end, a draft passage formed centrally in the opposite end, a pair of semi-circular spring clamping members having a tongue provided at right angles thereto and embedded in the edge of the holder surrounding the cigar receiving end, said spring clamping members cooperating to form a clamping band for retaining a secure grip upon the cigar until the same has been consumed.

In testimony whereof, I have affixed my signature.

LEWIS BERGAN.
